His Attorney.

UNITED STATES PATENT OFFICE

JEREMIAH FLYNN, OF ST. LOUIS, MISSOURI, ASSIGNOR OF ONE-FOURTH TO FRANK TIRRELL AND ONE-FOURTH TO JEROME FLYNN, BOTH OF ST. LOUIS, MISSOURI

REFRIGERATOR

Application filed June 26, 1929. Serial No. 373,823.

This invention relates to refrigerators.

An object of the invention is to provide means for embodiment in refrigerators for opening and closing communication between the compartments of the refrigerators automatically and as an incident to the operation of the doors of the different compartments. For this purpose I provide slides controlling communication between the respective compartments and levers for moving the slides to opened and closed positions so as to open and close communication between said compartments, and means operated by doors to the respective compartments for operating said levers so as to operate said slides to open communication between the compartments automatically and as an incident to the closing of the doors and to permit said slides to be moved to closed position automatically and as an incident to the opening of the doors.

Another object of the invention is to provide units adapted for convenient insertion and withdrawal in a refrigerator for controlling communication between the respective compartments.

Other objects will appear from the following description, reference being made to the annexed drawings in which—

Fig. 1 is a front elevation of a refrigerator having my invention embodied therein.

Fig. 2 is a vertical sectional view approximately on the line 2—2 of Fig. 1.

Fig. 3 is an enlarged horizontal sectional view approximately on the line 3—3 of Fig. 1.

Fig. 4 is a sectional view of one of the walls and the cooperating unit showing the registering openings through the wall and the unit and the closure for said openings.

It will be apparent from the following description that the present invention is designed and adapted to be embodied in any refrigerator having separate compartments and doors for opening and closing the respective compartments. This invention will control communication between the respective compartments of the refrigerator in such a way as to open communication between the compartments when all of the doors of the

refrigerator are closed, and to close communication from the other compartments to any compartment the door of which is open.

The refrigerator shown will be recognized as of conventional type comprising a bottom wall 1, a top wall 2, a vertical side wall 3, an opposite vertical side wall 4, and a rear wall 5. There is a vertical partition 6 extending from the bottom wall 1 to the top wall 2 and joined to the side wall 3 by a horizontal partition 7. Thus the partitions 6 and 7 divide the interior of the refrigerator into a number of compartments consisting, as shown, of a compartment 8 above the partition 7, for the ice, a compartment 9 below the partition 7, and a compartment 10 between the side wall 4 and the vertical partition 6. The compartments 9 and 10 are designed and adapted to contain articles of food and beverages and other substances which are to be subjected to the cooling or refrigerating effect of the ice contained in the compartment 8.

A door 11 for opening and closing the compartment 8 is hinged to the side wall 3 of the refrigerator, and a door 12 for opening and closing the compartment 9 is hinged to the side wall 3. These doors may be opened and closed independently of each other. A door 13 for the compartment 10 is hinged to the side wall 4 of the refrigerator and may be opened and closed independently of either of the doors 11 or 12.

To obtain maximum cooling and refrigerating effect from the ice that is contained in the compartment 8, open communication from compartment 8 to the compartments 9 and 10 and also open communication between the compartments 9 and 10 is maintained when all of the doors of the refrigerator are closed. However, when the door 11 is opened, communication from the compartment 8 to both compartments 9 and 10 is closed. When the door 12 is opened while the doors 11 and 13 are closed, communication from the compartment 9 to the compartment 8 and from the compartment 9 to the compartment 10 is closed. And when the doors 11 and 12 are closed and the door 13 is opened, communication from the compartment 10 to the com-

partments 8 and 9 is closed. This prevents warm air from passing from either of the compartments, the door of which is opened, into either of the other compartments, and thus obtains maximum benefit from the supply of ice and keeps the contents of the refrigerator in better condition than would be the case if the contents were subjected to the effects of warm air when any of the doors of the refrigerator are opened.

The units for controlling communication between the compartments 8 and 10 and the units for controlling communication between the compartments 9 and 10 are alike so that 15 a description of one such unit will afford an understanding of all.

The partition 6 has therethrough an opening 14 near its upper portion to afford communication between the compartments 8 and 20 10, and has an opening 15 therethrough near its lower end to afford communication between the compartments 9 and 10. I provide a separate unit for controlling each of the 25 openings 14 and 15 by the door 13; a similar unit for controlling the opening 14 by the door 11, and a similar unit for controlling the opening 15 by the door 12. These units are alike and are independently operated and controlled by the respective doors. Each of 30 said units includes a box-like structure comprising two parallel walls 16 having holes therethrough.

The units for controlling communication between the compartments 8 and 10 each 35 comprise a pair of spaced walls 16 having openings therethrough in registration with the opening 14, the edges of said walls 16 being connected and said walls 16 held in spaced relationship by side walls 17 so that a box-like structure is obtained. These box-like 40 structures are readily insertable in and withdrawable from the refrigerator, being mounted at their lower edges on supporting brackets 18 and retained against the partition 6 at their upper edges by brackets 19. A vertical rod 20 is within each unit between the 45 walls 16 and constitutes a guide for a slide plate 21, having thereon a sleeve 22 mounted on the rod 20. A lever, comprising an arm 23 and another arm 24, is mounted on a pivot 50 25 between the side walls 16. The arm 23 has a pin and slot connection 26 with the sleeve 22, and the arm 24 has pin and slot connection 27 with a plunger 28. This plunger 28 is of such length that when the cooperating door is closed, said plunger 28 is engaged by the inner side of said door and pushed inwardly so as to operate the lever 23-24 and thereby move downwardly the 55 slide 21 away from the opening 14. A spring 29 between the walls 16 acts against the lever arm 23 with sufficient force and in a manner to move said arm 23 in a direction and to an extent to move the slide 21 to position to 60 close the opening 14.

As stated, one of these units is mounted in the compartment 8 for control by the door 11 and another of such units is mounted in the upper end of the compartment 10 for control by the door 13. Similarly one of such units is mounted in the compartment 9 for control by the door 12 to open and close the opening 15, and a similar unit is mounted in the compartment 10 for control by the door 13 to open and to close communication between the compartments 9 and 10. The only difference between the location and mounting of the units for controlling communication between the compartments 9 and 10, as compared with the units for controlling communication between the compartments 8 and 10, is that the units for controlling communication between the compartments 9 and 10 are inverted with respect to the units for controlling communication between the compartments 8 and 10. Otherwise these units are alike, the parts of the units for controlling communication between the compartments 9 and 10 being designated by the reference characters 16a, etc.

The partition 7 that separates the compartments 8 and 9 has therethrough an opening 30. For controlling this opening I provide duplicate units, one of which is in compartment 8 and is under control of the door 11, and the other of which is in the compartment 9 and under control of the door 12. Each of said units comprises a box-like structure including an upper wall 31, a lower wall 32 and side walls 33 joining the edges of the walls 31 and 32 and holding said walls in spaced relationship. The walls 31 and 32 have therethrough openings in registration with the opening 30 through the partition 7. A rod 34 is connected with the side walls 33 and extends transversely across the inside of the box-like unit. Two slides 35 have sleeves 36 mounted for sliding movements on the rod 4 and are movable to positions to open and to close the opening 30. Bellcrank levers 37 are mounted on pivots 38 within each unit and bellcrank levers have pin and slot connections 39 with the respective collars 36 and are operative to move said collars to and from position to close the opening 30. The bellcrank levers 37 are connected by a spring 40 which is effective to operate the bellcrank levers in a direction and extent to move the slides 35 to closed positions. The opposite arms of the bellcrank levers 37 have operative connections 41 with the plunger 42, which projects forwardly in position to be engaged by the door 11 or 12, as the case may be, when said door is closed. Thus when both doors 11 and 12 are closed the slides 35 of both units are held open. And when either door 11 or 12 is opened the slides 35 of the corresponding unit are closed by the spring 40, thereby closing the opening 30 constituting the communication between the compartments 8 and 9.

The unit in the compartment 8 is held in 130

position by brackets 43, and the unit in the compartment 9 is supported by brackets 44. Thus the units are easily removable and replaceable and, indeed, may be applied to most refrigerators as an accessory or addition.

5 From the foregoing the high degree of utility, and the construction and operation of the invention must be apparent. The construction and arrangement of parts may be varied within equivalent limits without departure from the nature and principle thereof. I do not restrict myself in any unessential respects but what I claim and desire to secure by Letters Patent is:

15 1. A refrigerator, partitions dividing the inside of said refrigerator into separate compartments and having openings therethrough forming communications between said compartments, slides operative to open and close said openings to open and close communication between said compartments, a rod extending across each of said openings, a sleeve in connection with each of said slides mounted for sliding movements along the corresponding rod, a bell crank lever corresponding to each of said slides, a pivotal connection between one arm of each bell crank lever and the corresponding slide, a plunger engaging the other arm of each bell crank lever, and doors for the respective compartments for engaging said plungers and holding said bell crank levers in position to hold said slides in open positions when said doors are closed.

35 2. A refrigerator, partitions dividing the inside of said refrigerator into separate compartments and having openings therethrough forming communications between said compartments, doors for the respective compartments, a box-like device having spaced walls provided with openings for registration with said openings through said partitions mounted in each of said compartments, means for removably supporting said box-like devices in the respective compartments in positions in which said openings through said devices register with said openings through said partitions, and valves mounted between said walls of said box-like devices for opening and closing said openings through said walls.

55 3. A refrigerator, partitions dividing the inside of said refrigerator into separate compartments and having openings therethrough forming communications between said compartments, doors for the respective compartments, a box-like device having spaced walls provided with openings for registration with said openings through said partitions mounted in each of said compartments, means for removably supporting said box-like devices in the respective compartments in positions in which said openings through said devices register with said openings through said partitions, valves mounted between said walls of said box-like devices for opening and

closing said openings through said walls, and actuating devices for said valves supported by said box-like devices and operated by said doors when said doors are closed to open said valves.

70 4. A refrigerator, partitions dividing the inside of said refrigerator into separate compartments and having openings therethrough forming communications between said compartments, spaced walls forming a box-like device having openings therethrough, means removably supporting one of said box-like devices in each of said compartments in position in which the openings through said box-like devices register with the openings through said partitions, doors for the respective compartments, valves mounted in said box-like devices for opening and closing said openings, and means for operating said valves by said doors to open said valves when said doors are closed.
